UNITED STATES PATENT OFFICE.

AUGUSTUS CICERO FELTON, JR., OF MACON, GEORGIA.

CREMATORY.

Application filed September 26, 1922. Serial No. 590,649.

To all whom it may concern:

Be it known that I, AUGUSTUS C. FELTON, Jr., a citizen of the United States, and a resident of Macon, in the county of Bibb and State of Georgia, have invented certain new and useful Improvements in Crematories, of which the following is a specification.

My invention relates to improvements in crematories, and it consists in the combinations, constructions and arrangements herein described and claimed.

An object of the invention is to provide a crematory which affords facilities for utilizing in the incineration of waste matter and refuse, practically all the heat generated within the crematory.

A still further object of the invention is to provide a crematory which is constructed in such manner as to permit pre-heating of the intake air for supporting combustion therewith by the heat of the exhaust gases and products of combustion, which heat would ordinarily escape from the crematory without accomplishing any useful purpose.

A still further object of the invention is to provide a crematory having means for conducting the heated products of the combustion a relatively great distance in contiguous relation to the walls of a combustion chamber of the crematory before permitting such products of combustion to pass from the crematory, whereby a high temperature is maintained within the combustion chamber and the accumulated heat within the crematory is utilized to a relatively great extent.

A still further object of the invention is to provide a crematory of simplified construction which embodies a novel and simple arrangement whereby fuel may be readily fed to the combustion chamber and the heat conducting passages of the crematory may be conveniently cleaned.

Other objects and advantages will be apparent from the following description, and the novel features of the invention will be particularly outlined in the appended claims.

My invention is illustrated in the accompanying drawings, forming a part of this application, in which:—

Fig. 1 is a horizontal sectional view taken through the lower portion of a furnace or crematory embodying the invention and through the walls of a structure associated with the crematory,

Fig. 2 is a fragmentary longitudinal vertical section taken through the structure shown in Fig. 1,

Figs. 3 and 4 respectively are fragmentary transverse sectional views of the opposite end portions of the crematory and associated structure,

Figs. 5 and 6 respectively are sections taken substantially on the lines 5—5 and 6—6 of Fig. 2,

Fig. 7 is a fragmentary view, partly in section and partly in side elevation, showing a portion of the crematory, a ventilator provided therein and a hot water tank positioned at one end of the crematory, and

Fig. 8 is an end view of the structure shown in Fig. 7, portions thereof being broken away to show that the heating coils of the water tank are disposed within a flue of the crematory.

Referring now to the drawings and more particularly to Figs. 1, 3 and 4 thereof, it will be observed that the invention contemplates the provision of a combustion chamber A having side walls A¹ and A² and end walls A³, A⁴ surmounted by a roof A⁵ which is arched between the side walls, as is usual in furnaces of the reverberatory type of construction.

The bottom or floor of the combustion chamber A consists of a grate section A⁶ upon which fuel may be placed and consumed and a pan or hearth section A⁷ for supporting night soil, wet garbage and other refuse for incineration. The grate section A⁶ overlies an ash pit A⁸ with which a series of clean-out openings A⁹ formed through the wall A¹ communicate. A plurality of openings A¹⁰ are formed through the wall A¹ with their bases or bottom walls in the plane of the upper side of the grate section A⁶ so that fuel may be conveniently fed to the grate section. The openings A¹⁰ preferably correspond in number with the openings A⁹ and are relatively arranged so that a fuel feed opening is provided above each of the clean-out openings A⁹. Doors A¹¹ are provided to control the clean-out openings A⁹ and the openings A¹⁰ are normally closed by doors A¹².

It is to be observed at this point that the upper sides of the juxtaposed lower sections A⁶ and A⁷ lie in substantially the same horizontal plane and that each occupies approximately half of the area of the bottom of the combustion chamber.

A stack or chimney S is located at one end of the combustion chamber A and is in open communication at its lower end with horizontal flues F which extend beneath the pan section A⁷ the entire length of the combustion chamber. The flues F are in communication at their ends remote from the stack with the interior of the combustion chamber at the end of the latter remote from the stack through angular ports or passages P (see Figs. 1, 2 and 3), the lower sides of the horizontal portions of the angular passages P lying in planes coinciding substantially with the plane of the upper edge of the adjacent end of the pan section A⁷. Clean-out openings O permitting access to the adjacent end portions of the flues F are provided in the wall A⁴ and similar clean-out openings O' affording access to the lower part of the stack S and to the portions of the flues F adjacent to the stack are provided through a wall of the stack adjacent to the lower end of the latter.

As shown in Figs. 2, 3 and 4, the side and end walls of the combustion chamber extend above the plane of the highest part of the arched roof A⁵ and support above the latter a section K of a charging floor, thus providing an air space L which overlies the combustion chamber. Ventilators V in the walls A¹ and A² provide a means for admitting air to the space L. Any desired number of the ventilators V may be provided.

By referring to Figs. 2 and 6, it will be noted that the arched roof A⁵ of the combustion chamber is offset downwardly at one end to provide a horizontally disposed wall M extending transversely of the combustion chamber at one end of the latter and constituting the upper wall of the horizontal portion of the passages P as well as the bottom wall of a horizontal pre-heating passage N which communicates at its one end through an opening N¹ with the air space L at one end of the latter and communicates at its other end with a downwardly extending passage N². The latter communicates at its lower end through an opening N³ with the space below the grate section 6 at one end of the latter or in other words with the ash pit A⁸.

The air space L is in communication at its end remote from that communicating with the opening N¹ with a downwardly extending passage Q which communicates at its lower end with a horizontally extending pre-heating passage R. The latter extends transversely of the combustion chamber and communicates with the end of the ash pit A⁸ proximate to the stack S through a downwardly extending passage R' and an opening R².

It is to be observed that the openings R² and N³ are located adjacent to the side of the combustion chamber provided with the

ventilators V and that the transverse pre-heating passages N and R communicate with the air space L at points adjacent to the opposite side of the combustion chamber. Baffle walls L' extending longitudinally of the air space L may be provided to cause the air entering through the ventilators V to travel circuitously before entering the passages N¹ and Q.

The walls of the combustion chamber, which have been described, may be made of fire brick or like material and may have dead air cells or chambers A¹² provided therein so that heat will be stored within these walls and the latter kept in a heated condition during the operation of the crematory.

The crematory structure described may be disposed within and associated with certain of the walls of a housing structure, which is indicated generally at T and is best seen in Fig. 1. The charging floor section K may extend beyond the plane of certain of the vertical walls of the crematory structure, as shown in Figs. 3, 4, 7 and 8. The form of the crematory structure and the housing structure may vary considerably from that shown without departing from the spirit and scope of the present invention and in fact, the housing structure may be omitted if desired.

The charging floor section K may be provided with a chute such as that indicated at X in Fig. 3, which chute is preferably circular in cross sectional contour and depends through the arched roof A⁵ in such position that garbage, night soil and other refuse may be dumped therethrough upon the pan A⁷.

It is desirable that use may be made at points remote from the crematory of some of the heat created and stored within the crematory. To this end, liquid conducting coils Y may be positioned within one of the flues F and may have connection through suitable pipes Y' with a storage tank Y², which is positioned exteriorly of the crematory structure and which may be connected in any suitable known manner with a source of liquid supply and with means (not shown) for conducting the heated liquid to a desired place.

In order to facilitate combustion in the combustion chamber, a liquid fuel may be introduced therewithin through the agency of a liquid fuel injecting or feeding arrangement extending through the wall A¹ above one or each of the fuel feed openings A¹⁰. One type of liquid fuel feeding device is shown more or less diagrammatically in Figs. 4 and 7 and is denoted generally by the reference character Z, being connected with a liquid fuel supply conduit Z'. A liquid fuel discharged from the feeding mechanism Z will be sprayed from the grate section A⁶ and upon solid hydro-carbon fuel thereon, whereby combustion of such solid fuel will be facilitated and the temperature

within the combustion chamber will be increased to a relatively high degree in a minimum of time.

The crematory structure may be braced and reenforced by vertical brace members or buck bars W arranged at opposite sides thereof and being connected by the rods W' extending through the side walls of the crematory structure.

From the foregoing description of the various parts of the device, the operation thereof may be readily understood. Wet garbage, night soil and other refuse which are to be incinerated, may be dumped through the chute or chutes X upon the pan A⁷. A suitable fuel, introduced within the combustion chamber through the fuel feed openings A¹⁰ to rest upon the grate section A⁶ is ignited in any suitable known manner and the combustion thereof may be supported at the beginning of the operation or throughout the operation if desired, by a more readily combustible fuel, such as oil, fed to the flame by the liquid fuel feeding mechanism Z. Air supporting the combustion enters the space L through the ventilators V and passes therefrom through the passages Q, R, R', R² and N¹, N, N², N³ to the space beneath the grate section A⁶ at opposite ends of the latter. It is to be observed at this point that the intake air is heated because of contact with the arched roof A⁵ in passing from the ventilators V to the passages Q and N¹. The intake air is further heated during its passage along the passages Q, R, R' and N¹, N, N², being heated to a relatively high temperature because of contact with the walls of the pre-heating passages R and N, which are heated in a manner to be hereinafter described.

The heated intake air passes upwardly through the grate section and supports combustion in the usual manner. The heated products of combustion pass from the grate section A⁶ along the surface of the pan A⁷ and the refuse thereon to the openings or passages P which are located at the end of the pan remote from the stack S. As stated, the bottom wall of the passage N is the upper wall of the passages P and in consequence, the walls of the pre-heating passage N are kept continuously at a relatively high temperature by heat from the gases and products of combustion passing through the exhaust passage P. The passages P communicate with the flues F at the ends of the latter remote from the stack S and the heated products of combustion must therefore travel the entire length of the combustion chamber in underlying proximity to the pan A⁷ before such products of combustion are permitted to enter the stack S.

The walls of the pre-heating passage R are maintained in heated condition because of their proximity to the stack S and to the

flues F which underlie the bottom wall of the passage R, as best seen in Fig. 2.

It will thus be apparent that practically all the heat created by the combustion of a given amount of fuel within the combustion chamber is utilized in the drying and incineration of garbage and other refuse dumped upon the pan A⁷. The heated gases and other products of combustion are conducted by a circuitous route from the combustion chamber to the stack and the heat from such products of combustion is utilized to dry the wet garbage and other refuse upon the pan A⁷ to cause a direct contact therewith, to keep the walls of the combustion chamber and the pan A⁷ heated and to therefore effect the pre-heating of intake air before the latter reaches the grate section and the thorough drying of the matter which is to be incinerated. A relatively high temperature is thus maintained continuously within the combustion chamber and a crematory having relatively high efficiency is thus provided.

The arrangement of the grate section 6 and the feed and clean-out openings associated therewith is such as to permit of fuel being supplied conveniently to the grate section and the convenient and easy cleaning of the ash pit. Moreover, the provision of the clean-out openings at the ends of the flues F permits of the cleaning of these flues and prevents the accumulation therein of carbon deposits or like matter which might detrimentally affect the operation of the device.

Obviously my invention is susceptible of embodiment in forms other than that in which illustrated in the accompanying drawings, and I therefore consider as my own all modifications and adaptations thereof which fairly fall within the scope of the appended claims.

I claim:—

1. A crematory structure comprising vertical side and end walls, a charging floor section supported upon the vertical side and end walls, a floor consisting of juxtaposed grate and garbage supporting sections, an arched roof overlying the floor and being spaced from the charging floor, said side wall having an inlet therein for admitting air to the space between the roof and the charging floor, walls cooperating with the said end walls and the arched roof for conducting the admitted air by tortuous paths from the inlet to a space below the grate section, a stack adjacent to one of said end walls, said garbage supporting section having a flue extending longitudinally thereof in adjacent underlying relation to the supporting surface thereof and being spaced from the end wall of the crematory remote from the stack to provide a port establishing communication between the one end of

110

115

120

125

130

said flue and the space within the crematory structure below the arched roof, said flue being in open communication at its opposite end with the stack, and a charging chute depending from the charging floor through the arched roof.

2. A crematory structure having a combustion chamber including a roof and provided with a floor consisting of juxtaposed 10 grate and garbage supporting sections, and a pre-heating chamber overlying the roof, said pre-heating chamber having an inlet for air and an outlet remote from the inlet, said outlet leading to the space beneath the 15 grate section, said combustion chamber having a discharge conduit extending for part of its length in underlying relation to said outlet of the pre-heating chamber, as and for the purpose set forth.

20 3. A crematory structure comprising superposed combustion and pre-heating chambers, the pre-heating chamber being uppermost and being provided with spaced apart inlet and outlet conduits, and the combustion chamber being provided with a floor comprising juxtaposed grate and garbage supporting sections, said outlet conduit

opening into the space below the grate section, said combustion chamber having a discharge conduit extending for part of its 30 length in contiguous relation to the outlet of the pre-heating chamber, and baffle walls in the pre-heating chamber for causing the air admitted thereinto to travel by a tortuous path to the outlet of the pre-heating 35 chamber.

4. In a crematory, a combustion chamber having a floor consisting of juxtaposed grate and garbage supporting sections and having a roof, and a pre-heating chamber overlying the combustion chamber, said pre-heating chamber having an inlet and an outlet conduit leading to the space beneath the grate section, said outlet conduit extending for part of its length transversely of the combustion chamber and said combustion chamber being provided with a discharge conduit having the intake end thereof located in underlying adjacent relation to the transversely extending portion of the outlet of 50 the pre-heating chamber, said discharge conduit then extending in underlying relation to the garbage supporting section.

AUGUSTUS CICERO FELTON, JR.
